P. H. CONNEIGHTON

POCKET FOLDER

Filed Nov. 22. 1921

Inventor
Patrick H. Conneighton
By
Walter H. Murray
Attorney

UNITED STATES PATENT OFFICE.

PATRICK H. CONNEIGHTON, OF SOUTH NORWOOD, OHIO.

POCKET FOLDER.

Application filed November 22, 1921. Serial No. 517,141.

To all whom it may concern:

Be it known that I, PATRICK H. CONNEIGHTON, a citizen of the United States of America, and resident of South Norwood, in the county of Hamilton and State of Ohio, have invented a new and useful Improvement in Pocket Folders, of which the following is a specification.

An object of my invention is to provide a simple and efficient folder or case adapted to secure loose sheets of foldable material, such as paper, in an orderly manner, so that same may be readily carried in a pocket without injury to such sheets.

Another object is to provide a device of the kind referred to, wherein the loose sheets may be easily and quickly secured and wherefrom the sheets may be easily and readily released or detached.

These and other objects are attained by the device shown.

Fig. 1 is a view showing in an extended position, a folder embodying my invention.

Fig. 2 is an enlarged view of parts shown in Fig. 1 showing in an extended position the jaws forming details of my invention.

Fig. 3 is a sectional view of parts shown in Fig. 2, the movable jaw being in a partly extended position.

Fig. 4 is a perspective view, on a reduced scale, showing in a folded position, a folder embodying my invention.

My invention comprises a foldable cover A, having mounted upon it a sheet holder B adapted to secure several sheets C, and a lock D adapted to secure the jaws of the holder in their operative or binding positions.

The cover or backing A may be made of any suitable foldable, and preferably flexible, material such as leather. If desired the folder may comprise several pieces of material such as cardboard, which may be hingedly mounted upon one another so as to be foldable upon one another along lines corresponding to the lines a and a'. The cover comprises end portions a² and a³, between and connected with which is an intermediate portion a⁴. The end portions are bendable or foldable upon the intermediate portions along the lines a and a' whereby the end portion a³ may extend over, or overlap the end portion a² as shown in Fig. 4. The end portions carry complementary sections a⁵ and a⁶ of a suitable snap fastener or other fastening means whereby the end

portions may be secured in such overlapping relation.

The end portion a² which underlies the end portion a³ has mounted on it a plate b which forms one of the jaws of the holder B. This jaw or plate may be secured upon the cover in any suitable manner, such as by means of rivets b', so that the outer end b² of said jaw extends substantially parallel with the edge a⁷ of the cover, and is spaced a short distance beyond the edge a⁷. The jaw b has pivotally mounted upon it, along its edge b², a jaw b³ complementary to and substantially coextensive with the jaw b. The jaw b³ is provided with an arcuate flange b⁴ extending longitudinally of itself. The jaw b and flange b⁴ carry complementary teeth or pins b⁵ adapted to be brought into cooperative engagement upon sheets of foldable material, such as paper, that are to be contained by the folder.

The jaw b has pivotally mounted on it a lock or clamp D comprising a U shaped clip consisting of a body d and sides d', d². The clip has spring qualities, wherefor the sides or arms of the clip may be sprung in relation to one another and to the body. The arm d² is elongated at one end, whereby a lug d⁵ is formed thereon. The lug is pivotally mounted on the jaw b by any suitable means such as the rivet d⁶. The free end d⁴ of the arm d² is flared outwardly or away from the arm d. The arms d² and d¹ are spaced from one another at a distance substantially equal to the distance between the outer faces of the jaws b' and b³ when folded upon one another as shown in Fig. 1.

To secure sheets C in the folder or to remove some of the sheets from the same, the clip is moved about its pivotal mounting so that it extends longitudinally away from the cover A, or in other words is extended substantially at right angles to the edge a⁷ of the cover. The jaw b³ is then moved upon its pivotal mounting on jaw b to an extended position as shown in Fig. 3. The sheets C then have their upper ends c laid upon or removed from over the jaw b. The sheets are disposed upon the jaw in such position that the teeth b⁵ may engage the sheets, adjacent the upper ends of such sheets. After the sheets have been removed from or disposed upon the jaw b, the jaw b³ is brought into engagement with the sheets lying on jaw b, and the clip is then moved upon its pivotal mounting, the arm d² engaging jaw b.

and arm d^2 engaging jaw b^3 and both arms extending in substantial parallelism with the edge a^7 of the cover. The spring qualities of the clip cause the arms to clamp the jaws in binding relation upon the sheets, and the teeth on the jaws fix the sheets against movement between the jaws.

What I claim is:

In a device of the class described the combination of a foldable cover, a pair of jaws hingedly connected along their edges and provided with co-operating means adjacent their free edges for securing papers between the free ends of the jaws, one of the jaws being mounted along its free edge of the

cover, and a U-shaped clip comprising resilient branches between which the jaws may be yieldingly received when in their closed position, one of the branches having an extension pivotally mounted on the jaw carrying the cover, whereby the clip may be moved to an extended position for freeing the jaws and to a locking position for clamping the jaws and to permit enclosure of the jaws, clip, and papers within the cover.

In testimony whereof I have hereunto subscribed my name this 18th day of November, 1921.

PATRICK H. CONNEIGHTON.
